UNITED STATES PATENT OFFICE.

CHARLES L. WARD, OF CAVENDISH, VERMONT.

CAR-DOOR.

SPECIFICATION forming part of Letters Patent No. 404,755, dated June 4, 1889.

Application filed October 4, 1888. Serial No. 287,177. (No model.)

To all whom it may concern:

Be it known that I, CHARLES L. WARD, a citizen of the United States, and a resident of Cavendish, in the county of Windsor and State 5 of Vermont, have invented certain new and useful Improvements in Car-Doors; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a representation 15 of this invention, and shows a portion of the side of a car with the door. Fig. 2 is a side view showing portions of the door with its tracks. Fig. 3 is a vertical section through the upper and lower portions of the door with 20 its tracks or ways.

The invention relates to improvements in doors for freight-cars; and it consists in the construction and novel combination of parts, as hereinafter set forth. The object is to so 25 construct the door that it will run easily on its track or way, and also to so form the runner-way that the door will be protected thereby from displacement.

Referring by letter to the drawings, A designates the side of a car, and B is the door 30 opening therein.

C is the lower way or track for the door D, consisting of a strip of wood about twice the length of the door and bolted or otherwise secured to the car-side. E is a similar way at 35 the top of the door, and F is a stop-casing at

one end. Metal flanges G are secured to each way and project over the edge of the door, as shown, and hold the said door from displacement. The lower way C may have a metal 40 plate H on its upper face to prevent wearing away.

The door D, at the top and bottom, has the transverse recesses I, within which are placed the rollers J. The rollers J project slightly 45 beyond the edge of the door, so that the edge will not bear upon the ways, and the journals K of the rollers have bearings through the plates L, which are seated in recess M in the sides of the door, so that the outer surface of 50 the plates will be flush with the surface of the door.

Having described my invention, what I claim is—

In a car-door, the combination, with the 55 door, of bearing-plates seated in recesses in the door, rollers arranged in transverse recesses in the top and bottom edges of the door, journaled in the bearing-plates, and projecting beyond the edges of the door, the 60 guideways applied to the car-body, having outer flanges projecting toward each other and lapping the outer roller bearing-plates, and a plate secured to the upper bearing-surface of the lower guideway, substantially as 65 set forth.

In testimony whereof I affix my signature in presence of two witnesses.

CHARLES L. WARD.
